UNITED STATES PATENT OFFICE.

ANDREW POETZL, OF DOVER, NEW JERSEY.

SOCK OR STOCKING.

No. 820,989.

Specification of Letters Patent.

Patented May 22, 1906.

Application filed April 17, 1906. Serial No. 312,114.

To all whom it may concern:

Be it known that I, ANDREW POETZL, a citizen of the German Empire, residing at Dover, Morris county, State of New Jersey, have invented new and useful Improvements 5 in Socks or Stockings, of which the following is a specification.

This invention relates to a sock or stocking provided with a reinforcing toe-cap which 10 greatly prolongs the life of the fabric.

In the accompanying drawings, Figure 1 is a side view of the foot of a sock or stocking embodying my invention; Fig. 2, a longitudinal section through the toe portion thereof; Fig. 3, a cross-section on line 3 3, Fig. 2; and Fig. 4, a section similar to Fig. 2, showing the toe unlooped.

The letter a indicates the foot of a sock or stocking the sole, heel, and toe of which are 20 reinforced in the usual manner, the reinforcement of the toe extending to the line a' . Within the tip of the stocking is inclosed a knitted cap b , which is shorter than the reinforced section of the toe, extending to the line b' . The cap b is preferably of the same 25 thickness as the reinforced section of the stocking. It is connected thereto by interlooping at its apex b^2 and also at its base b' ,

but is disconnected therefrom between apex and base. During manufacture the apex of 30 the cap b is slightly set back from the tip of the toe, Fig. 4, so that a strip of meshes a^2 of the tip of the toe projects beyond the meshes 35 of the cap. These projecting meshes a^2 are interlooped to close the stocking, Fig. 2, the construction described preventing undue thickness at the tip of the finished article.

It will be seen that by my invention the toe is effectively reinforced and that the foot must wear through two separate and distinct 40 knitted layers before the stocking is worn through.

What I claim is —

The combination with the toe of a stocking, of a cap within the toe formed of a separate thickness of material and secured to the toe at its base and apex, the meshes of the toe at its apex being extended and interlooped beyond the apex of the cap.

Signed by me at New York city, New York, 50 this 16th day of April, 1906.

ANDREW POETZL.
